(57) **CLAIM**

The ornamental design for a sport camera component, as shown and described.

DESCRIPTION

FIG. 1 is a top, front and left side perspective view of a sport camera component showing my new design;

FIG. 2 is a top, front and right side perspective view thereof;

FIG. 3 is a bottom, rear and right side perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof;

FIG. 9 is a bottom plan view thereof; and,

FIG. 10 is a bottom, rear and right side perspective view thereof, shown with the sport camera component in condition of use.

The broken lines in the drawings depict portions of the sport camera component that form no part of the claimed design.
